DESIGN FOR A FRAME FOR PLAYGROUND EQUIPMENT

Benjamin F. Leber, Chicago, Ill., assignor to
Sears, Roebuck and Co., Chicago, Ill., a corpora-
tion of New York

Application September 10, 1945, Serial No. 121,973

Term of patent 14 years

(Cl. D34—5)

To all whom it may concern:

Be it known that I, Benjamin F. Leber, a citizen of the United States of America and a resident of Chicago, county of Cook, and State of Illinois, have invented a new, original, and ornamental Design for a Frame for Playground Equipment, of which the following is a specification, reference being had to the accompanying drawing, forming a part thereof.

Fig. 1 is a perspective view of my new design for a frame for playground equipment;

Fig. 2 is an enlarged fragmentary perspective view of a portion of the frame for playground equipment shown in Fig. 1; and

Fig. 3 is an enlarged fragmentary end elevational view thereof.

I claim:

The ornamental design for a frame for playground equipment, substantially as shown.

BENJAMIN F. LEBER.
